UNITED STATES PATENT OFFICE.

GEORGE G. SPENCER, OF CHICAGO, ILLINOIS.

DESIGN FOR A BICYCLE SEAT-POST.

SPECIFICATION forming part of Design No. 31,828, dated November 14, 1899.

Application filed October 23, 1899. Serial No. 734,589. Term of patent 7 years.

To all whom it may concern:

Be it known that I, GEORGE G. SPENCER, a citizen of the United States, residing at Chicago, in the county of Cook and State of Illinois, have invented and produced a new and original Design for Bicycle Seat-Posts, of which the following is a specification, reference being had to the drawings forming a part thereof.

- Figure 1 is a side elevation of a seat-post embodying this design. Fig. 2 is a rear elevation of said post. Fig. 3 is a plan view of the same; and Fig. 4 is a front elevation of the upper end of the post, showing the forward end of the tubular horizontal member.

As shown in the drawings, the leading or material features of my design consist in the form or configuration of a seat-post, wherein A is the stem of the post and B the horizontal member thereof, both which stem and horizontal member are tubular in form. The stem A and the horizontal member B are joined together at an angle somewhat less than a right

angle, and the sides of the stem at said point of junction are cut away, as at C, upon a 25 curve, which forms, with the periphery of the horizontal member, an ogee curve. The line which separates this ogee curve from the cylindrical surface of the stem A is sharp and well defined. At the exterior (rear) angle of 30 the junction between said stem and said horizontal member a portion of the latter is removed, providing a shoulder D, the larger surface of which shoulder extends at right angles to the length of the stem A and has an 35 opening E on the axial line of said stem. The forward end of the horizontal tubular member B is rounded inside and out to give it a finished appearance.

I claim as my invention—

The design for a bicycle seat-post substantially as herein shown and described.

GEORGE G. SPENCER.
